CLAIM

The ornamental design for a water tank, as shown and described.

DESCRIPTION

FIG. 1 is a front, left, top perspective view of a water tank showing our new design;

FIG. 2 is a front, left, bottom perspective view thereof;

FIG. 3 is a top plan view thereof;

FIG. 4 is a bottom plan view thereof;

FIG. 5 is a front elevation view thereof; and,

FIG. 6 is an enlarged perspective view of the top handle feature shown in FIG. 1.

The broken lines in the drawings depict portions of the water tank that form no part of the claimed design.

1 Claim, 6 Drawing Sheets(56)
